UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC-LAMP CLUSTER.

SPECIFICATION forming part of Letters Patent No. 760,375, dated May 17, 1904.

Original application filed December 9, 1901, Serial No. 85,206. Divided and this application filed March 3, 1902. Serial No. 96,480. (No model.)

To all whom it may concern:

Be it known that I, REUBEN B. BENJAMIN, a citizen of the United States, residing at Chicago, in the county of Cook and State of Illinois, have invented a certain new and useful Improvement in Electric-Lamp Clusters, of which the following is a full, clear, concise, and exact description, reference being had to the accompanying drawings, forming a part of this specification.

This application is a division of my application filed December 9, 1901, Serial No. 85,206.

It relates to improvements in electric-lamp clusters, more particularly to the feature of separate or individual contact-plates for the lamps, whereby various combinations and circuit arrangements of the lamps may be secured and whereby a greater degree of flexibility in the number of lamps to be accommodated in a single cluster is obtained.

Other features relate to the mode of securing the inclosed cap of the cluster in place.

In the accompanying drawings, in which the same reference characters designate like parts throughout the several views, Figures 1 and 2 are respectively bottom plan and sectional elevations of a two-light cluster of ordinary form. Figs. 3 and 4 are sectional and bottom plan views, respectively, of a four-light cluster. Fig. 5 is a sectional view similar to Fig. 3, except that the removable cap is held upon the cluster by the insulating-bushings alone. Fig. 6 is a bottom plan view of a four-light cluster in which the lamps are arranged in the electric circuit in series; and Fig. 7 is a plan view of a five-light cluster, showing various arrangements of the circuit connections.

Referring to Figs. 1 and 2, the insulating-base 2, preferably of porcelain, is provided with a centrally-depressed portion 3, upon the lower end of which a strip 4 is mounted, having the spring ends 5, which serve as central contacts for the lamps, a screw 5^a being inserted through said portion 3 of the base and preferably threading directly into the plate or strip 4. Upon the inner face of the insulating-base 2 individual contact plates or rings

6 are mounted and are secured thereto by the screws 7, threading into the inwardly-turned ends 8 of the contact-plates 6. The inner and 50 approached ends of these plates are secured together by the insulating-block 9 by means of suitable screws 10. Threaded metallic shells 11 are secured to the contact-plates 6 and serve as outer or sleeve contacts for the incandescent lamps and to hold said lamps in position. 55 Upon one side of each of the contact-plates 6 a lip or projection 12 is formed, in which is located a binding-screw 13, to which the end of the circuit-wire may be secured. Provision is made to bring the circuit-wire to the binding-post 13 through a suitable aperture 14 formed in the base 2 adjacent the binding-screw 13. A suitable metallic cap 15 for the cluster is provided and is adapted to be held 60 in the position shown in Fig. 2 by means of the insulating-bushing 16, also preferably of porcelain. It will thus be seen that the insulating-bushings serve to insulate the cap 15 from the shells to hold the cap in place upon 65 the cluster and also to accurately align the openings through the cap with the shells of the lamp connections. Suitable apertures 17 are formed in the base, through which screws may be passed to secure the cluster in position 70 in any desired place. When the lamps are inserted in the sockets and screwed into the shells 11, their outer contacts are in electrical connection with the shells 11 and their inner contacts with the spring-tongues 5. The electric circuit of the cluster is then from one circuit-terminal to a binding-post 13, through the corresponding contact-plate 6, the threaded shell in connection therewith, and through the lamp placed in the socket. From the center 75 contact of the lamp it passes to the spring-tongue 5 and thence to the opposite spring-tongue in connection with the other socket and through the lamp to the threaded shell 11 and opposite contact-plate 6. From here the circuit is extended, by means of the strip 12 and binding-post 13, to the other side of the circuit. 80 The lamps are thus seen to be in series 85 in this form of the cluster. 90

In Figs. 3 and 4 a larger base 2^a is provided, having the depressed center, as shown in Fig. 3, which supports the inner approached or adjacent ends of the individual contact-plates as well as the center contacts for the lamps. A ledge 20 is formed upon the base to carry the supporting plate or ring 21, having the extending spring-contacts 22 for the center contacts of the lamps. This ring is secured to the base by screws or bolts 23. The base is further extended or depressed centrally, so as to support the inner ends of the individual contact-plates 6, which are supported upon the ledge 24 of the base, a suitable metallic ring or plate 25 being placed beneath the said ends of the contact-plates 6 and screws, such as 26, being threaded through the base, the ring 25, and into the said inner ends of the contact-plates, whereby they are mechanically supported and electrically secured together. The outer ends 8^a of the contact-rings 6 are extended outwardly and are firmly secured to the base by means of the screws 7. A binding post or screw 27 is secured to one of the contact-plates, while a similar screw 28 is connected with the inner contact-ring 21. Suitable apertures 29 are provided in the base, through which the leading-in wires may be brought to the binding-post, as many of these apertures as desired being provided. As shown in these figures, the lamps are connected in parallel for the reason that the inner contacts are all electrically connected with one side of the circuit, and the outer contacts are all connected together by the metallic ring 25 and thence to the other side of the circuit. Each of the contact-plates 6 is provided with threaded shells 11 to receive the lamp-bases, upon which are screwed insulating-bushings 16, which are designed to insulate the shells from the cap 15 of the cluster to serve to align the apertures in the cap with the metallic shells and to assist in holding the cap in position upon the cluster. A central screw 30 is secured to the base and threads at its lower end into a nut 31, rigidly secured in the shell portion of the cap to assist in holding the cap in position upon the cluster. A jam-nut 32 is provided to hold the screw 30 in fixed position. In order to secure the cap in place, the screw 30 is first placed in position upon the base, and the cap 15 is turned upon a screw 30. The insulating-bushing 16 may then be placed in position, and the cap is thus securely held.

Fig. 5 shows substantially the same arrangement of the cluster as in Figs. 3 and 4, except that the cap 15 is held in position upon the cluster solely by the insulating-bushings 16, which in this instance are provided with overlapping shoulders 33, which serve to firmly bind the cap in place.

In Fig. 6 substantially the same construction of the base as in Fig. 3 is shown. The 65 lamps, however, are adapted to be connected

in series in the circuit. In this case the leading-in circuit-wire 35 is brought in through one of the apertures 29 in the base and is attached to the binding-screw 27. From this point the circuit is completed, through the 70 lamp adapted to be placed in the socket corresponding to the contact-plate 6, to the center contact 22 of the socket. This center contact is formed integrally with a metallic segment 36, carried by the base 2^a upon the ledge 20. 75 The center contact of the second lamp of the series is likewise formed integrally with the segment 36, from which the circuit is completed through the succeeding lamp to the corresponding outer contact-plate 6. The inner end of this lamp is secured to a metallic segmental strip 37, carried upon the ledge 24 of the base 2^a. The inner end of the contact-plate 6 of the next succeeding lamp of the cluster is secured to this same segment by 80 means of a suitable screw, as shown in Fig. 3, from which the circuit is completed through the lamp to the center contact, which is formed in connection with the metallic strip 36^a, mounted upon the ledge 20 of the base. The 85 fourth lamp of the series now completes the circuit from the center contact to the outside contact and to the binding-screw 27^a, with which one of the circuit-wires is connected and by means of which the circuit of the 90 series is completed. It will thus be seen that all of the lamps of the cluster are connected in series. It will be understood that the metallic shells 11 of the cluster have been omitted merely for the sake of clearness and that 95 while the center contacts have been described as being formed integral with the segments 36 and 36^a it is apparent that other suitable arrangements could be employed. The inner ends of the first and last contact-plates of the 100 series described are secured directly to the ledge 24 of the insulating-base, while the corresponding parts of the other contact-plates are 105 in electrical connection with the segment 37. 110

Fig. 7 shows the outline of the base of a cluster arranged to accommodate five lamps in a variety of circuit arrangements. For example, the contacts of the socket 40 are each provided with suitable binding-posts 27 and 45, by means of which this lamp may be connected in a circuit by itself. In the sockets 41 and 42 the contacts are arranged to be connected in multiple, as shown by the center and outer contact connecting strips 46 and 47, with which the circuit-wires 48 and 49 are connected. In the sockets 43 and 44 lamps are adapted to be connected in series by reason of the center-contact-connecting strip 50 and the binding-posts 51 and 52, secured to the inner ends of each of the contact-plates 6. 115 Suitable apertures are formed in the insulating-base to accommodate the said leading-in wires. It will also be understood from this figure that the threaded shells are omitted for clearness of illustration and that the base is 120 125 130

of substantially the same form as shown in Fig. 3.

It will thus be seen that I have provided a cluster which is extremely flexible and is capable of unlimited variation and as to the number of lamps accommodated and the circuit arrangement, and while I have described the same with particular reference to the details of construction I would have it understood 10 that it is not to be so limited, as various changes, modifications, and substitutions may be made therein and still not depart from its scope or principle.

Having described my invention, what I 15 claim as new, and desire to secure by Letters Patent, is—

1. In a lamp-cluster, the combination with a suitable base, of a plurality of individual contact-plates mounted upon said base, a 20 lamp-receiving shell mounted on each plate permitting the lamp-base to pass completely therethrough, a center contact for each lamp mounted upon said base and situated beyond the inner end of said shell and suitable means 25 for holding the lamps in operative position, substantially as described.

2. In a lamp-cluster, the combination with a suitable base, of a plurality of annular contact-plates mounted upon said base, a lamp- 30 receiving shell mounted on each plate permitting the lamp-base to pass completely therethrough, a center contact for each lamp mounted upon said base and situated beyond the inner end of said shell and suitable means 35 for holding the lamps in operative position, substantially as described.

3. In a lamp-cluster, the combination with a suitable base, of a plurality of individual contact-plates having sides oblique to the 40 base, a lamp-receiving shell mounted on each plate permitting the lamp-base to pass completely therethrough, center contacts for the lamps mounted upon said base and situated beyond the inner end of said shell and suitable 45 means for holding the lamps in operative position, substantially as described.

4. In a lamp-cluster, the combination with a suitable base, of a plurality of individual contact-plates oblique to the base having their 50 approached or adjacent ends secured together, and their opposite ends secured to the base, a shell mounted on each plate, center contacts for the lamps mounted upon said base and suitable means for holding the lamps in operative 55 position, substantially as described.

5. In a lamp-cluster, the combination with a suitable base, of a plurality of individual contact-plates secured at their outer and inner ends to said base, a lamp-receiving shell 60 mounted on each plate permitting the lamp-base to pass completely therethrough, and a center contact for each lamp mounted upon said base and situated beyond the inner end of said shell, substantially as described.

6. In a lamp-cluster, the combination with

a suitable base, of a plurality of individual contact-plates oblique to the base having their approached or adjacent ends secured together, and their opposite ends secured to the base, a lamp-receiving shell mounted on each plate 70 permitting the lamp-base to pass completely therethrough, a center contact for the lamps mounted upon said base and situated beyond the inner end of said shell, substantially as described. 75

7. In a lamp-cluster, the combination with a suitable insulating-base, of a plurality of individual contact-plates, a lamp-receiving shell mounted on each of said plates and permitting the lamp-base to pass completely 80 therethrough to engage a center contact also mounted on said base beyond the inner end of said shell, and binding posts or terminals formed integral with said plates, substantially as described. 85

8. In a lamp-cluster, the combination with a suitable base, of a plurality of individual contact-plates mounted thereon, a lamp-receiving shell mounted on each of said plates and permitting the lamp-base to pass completely 90 therethrough to engage a center contact also mounted on said base, beyond the inner end of said shell, and a binding post or terminal for one of the supply-wires formed integral with one or more of said rings, substantially as described. 95

9. In a lamp-cluster, the combination with a suitable base, of a plurality of individual contact-plates mounted thereon, a lamp-receiving shell mounted on each of said plates 100 and permitting the lamp-base to pass completely therethrough to engage a center contact also mounted on said base, beyond the inner end of said shell, means for securing said plates in position, and a lug formed on one or 105 more of said plates and integral therewith for connecting said plates with one of the supply-wires, substantially as described.

10. In a lamp-cluster, the combination with a suitable insulating-base, of a plurality of contact-plates, threaded contact-shells mounted on said plates and permitting the lamp-bases to pass completely therethrough, and center contacts for the lamps one for each shell mounted upon said base and situated beyond the inner ends of said shells, substantially as described. 115

11. In a lamp-cluster, the combination with an insulating-base of a plurality of individual contact-plates mounted upon said base in 120 inclined positions, a lamp-receiving shell mounted on each plate permitting the lamp-base to pass completely therethrough and a center contact for each shell mounted upon said base and situated beyond the inner end of said shell, substantially as described. 125

12. In a lamp-cluster, the combination with an insulating-base of a plurality of individual contact-plates mounted upon said base in inclined positions, the adjacent ends of said 130

- 1 plates being secured together, and the other ends secured to the base, a lamp-receiving shell mounted on each base, and a center contact associated with each plate, substantially as described.
- 5 13. In a lamp-cluster, the combination with a suitable insulating-base, of a plurality of individual contacts mounted thereon, and a binding-post in connection with one or more 10 of said contacts, said base being provided with an aperture situated within the circumference described by the outer ends of said contacts through which the leading-in wires may be brought, whereby the leading-in wires may 15 pass between said contacts to the binding-post, substantially as described.
14. In a lamp-cluster, the combination with an insulating-base, of a plurality of individual contact-plates mounted upon the front thereof, 20 lamp-receiving shells mounted upon each of said plates and metallic strips mounted upon the front of said base and connecting said plates together, substantially as described.
15. In a lamp-cluster, the combination with 25 an insulating-base, of a plurality of contact-plates mounted on the front of said base, a lamp-receptacle mounted on each plate, a center contact mounted upon the front of said base for each shell and metallic strips also 30 upon the front of said base and connecting said contacts in operative relation, substantially as described.
16. In a lamp-cluster, the combination with 35 an insulating-base, of a plurality of contact-plates mounted upon the front of said base, a lamp-receiving shell mounted on each of said plates permitting the lamp-base to pass completely therethrough, a center contact for each shell mounted upon the front of said base, and 40 metallic strips upon the front of said base connecting said contact-plates and said center contacts in operative relation, substantially as described.
17. In a lamp-cluster, the combination with 45 an insulating-base of a plurality of contact-plates, a center contact associated with each plate, said plates and center contacts all being mounted on the front of said base, a lamp-receiving shell mounted on each plate, and 50 metallic strips secured to said contacts and connecting them in operative relation, substantially as described.
18. In a lamp-cluster, the combination with 55 an insulating-base, of a plurality of individual contact-plates mounted on the base, a ledge formed on said base, center contacts for each contact-plate mounted upon said ledge, and an additional ledge formed on the base to which the outer ends of the contact-plates are 60 secured, substantially as described.
19. In a lamp-cluster, the combination with a suitable insulating-base, of a plurality of individual contact-plates mounted on the base, a lamp-receiving shell mounted on each plate, 65 a ledge formed on said base, a center contact for each shell mounted upon said ledge and an additional ledge formed on the base to which the outer ends of the contact-plates are secured, and strips arranged upon said ledges and connecting said contact-plates and said center contacts in operative relation, substantially as described.
20. In a lamp-cluster, the combination with 70 a suitable base, of a plurality of contact-plates mounted upon said base, a lamp-receiving shell mounted on each plate permitting the lamp-base to pass completely therethrough, a center contact arranged beyond the inner end of each of said shells and mounted on said base, a casing for said lamp-holding devices, 80 said casing having apertures or openings opposite each of said receiving-shells, substantially as described.
21. In a lamp-cluster, the combination with 85 a suitable base, of a plurality of contact-plates mounted thereon, a lamp-receiving shell mounted on each of said plates permitting the lamp-base to pass completely therethrough, a center contact associated with each of said shells and situated beyond the inner end thereof, a cover or casing for the lamp-holding device having an aperture opposite each of said lamp-receiving shells, and a bushing interposed between each of said shells and said casing, substantially as described.
22. In a lamp-cluster, the combination with 90 a suitable base, of contact-plates mounted thereon, a lamp-receiving shell mounted on each of said plates permitting the lamp-base to pass completely therethrough, a center contact for each lamp mounted upon said base and situated beyond the inner end of each shell, a casing for the lamp-holding devices having 95 an aperture opposite each of said lamp-receiving shells and a bushing arranged within each of said apertures or openings and supported by said shells, substantially as described.
23. In a lamp-cluster, the combination with 100 a suitable base, of a plurality of individual contact-plates mounted thereon and permitting the lamp-bases to pass completely therethrough to engage center contacts also mounted upon said base beyond the inner faces of said plates.
24. In a lamp-cluster, the combination with 105 a suitable base, of a plurality of individual contact-plates mounted thereon with the intermediate portions thereof arranged away from said base, said plates having the inner and outer ends thereof secured to said base, and center contacts mounted upon said base, whereby the lamp-bases must pass completely through said plates to engage said center contacts.
25. In a lamp-cluster, the combination with 110 a suitable base, of a plurality of individual contact-plates mounted thereon with the intermediate portions thereof arranged away from said base, said plates being secured at their 115

inner and outer ends to said base, a lamp-receiving shell supported by each of said plates and center contacts for said shell also mounted upon said base, whereby the lamp-bases 5 must pass completely through said shells and plates to engage the center contacts.

In witness whereof I have hereunto sub-

scribed my name in the presence of two witnesses.
